D'Arcy Porter INVENTOR

By
Lygett Lygett Attorneys

UNITED STATES PATENT OFFICE.

D'ARCY PORTER, OF CLEVELAND, OHIO, ASSIGNOR TO THE WHITE SEWING MACHINE COMPANY, OF SAME PLACE.

ROTARY-SHUTTLE-OPERATING MECHANISM.

SPECIFICATION forming part of Letters Patent No. 368,967, dated August 30, 1887.

Application filed April 9, 1887. Serial No. 234,268. (No model.)

To all whom it may concern:

Be it known that I, D'ARCY PORTER, of Cleveland, in the county of Cuyahoga and State of Ohio, have invented certain new and useful 5 Improvements in Rotary Shuttles for Sewing Machines; and I do hereby declare the following to be a full, clear, and exact description of the invention, such as will enable others skilled in the art to which it pertains to make and use 10 the same.

My invention relates to improvements in rotary shuttles for sewing-machines, but more especially in mechanism for advancing the shuttle to separate the heel of the latter from 15 the driver to allow the thread-loop to pass unobstructed between these parts.

My present invention is designed as an improvement on devices for which United States Letters Patent No. 358,750 were granted to 20 me March 1, 1887, and to which reference is made in this specification.

In the accompanying drawings, Figures 1 and 2 are respectively a front and side elevation, the latter being in section, of the parts 25 of a sewing-machine embodying my invention.

Fig. 3 is an end elevation of the head of the shuttle driving-shaft, showing the driver attached and showing the steady-pin and arm in position. Fig. 4 is a side elevation in section 30 corresponding in the main with Fig. 2, but showing in section the cam-rings for reciprocating the steady-pin. Fig. 5 is a plan in section, showing more especially a recess in the shuttle for receiving the end of the steady-pin arm. Fig. 6 is a front elevation of the shuttle 35 and driver in position detached. Fig. 7 is a side elevation, partly in section, showing more especially the steady-pin engaging the shuttle, the rearward position of these two parts being 40 shown in Fig. 2. Fig. 8 is a side elevation of the steady-pin and arm detached. Fig. 9 is an end elevation in section on the line xx , Fig. 4.

A represents the shuttle; B, the shuttle-race; 45 B', the race-cap; C, the shuttle-driving-shaft, and c the driver. The shuttle, between the point a and heel a', is cut away to receive the driver c, as shown in Figs. 1 and 6. The shuttle-race is cut away on top between the 50 points b and b'. The shuttle has a hub, A', on

which is mounted the bobbin D and bobbin-case D', all of which, together with the tension device d and swinging arm d', for holding the bobbin-case in place, may be of ordinary construction. The hub A' of the shuttle has a 55 central bore, a², and a recess, a³, is made at the periphery of the shuttle, as shown in Fig. 5. The shaft C is journaled in suitable boxes, F, connected with the cloth-plate F', only one of these boxes being shown. The shaft C has an 60 enlarged end or head, C', and has a longitudinal central bore, in which operates the pin E, the latter having an easy fit, so that it may move easily endwise. The reduced forward end e of the part E is adapted to enter the bore 65 a² of the shuttle to serve as a steady-pin for the latter. An arm, E', is connected with the pin E, the arm being shaped substantially as shown in Figs. 2, 3, 7, and 8, with the forwardly-projecting end beveled at e' and made to enter 70 the recess a³ of the shuttle.

The mechanism for reciprocating the pin E and arm E' is as follows: The pin E has a laterally-projecting stud, I, that extends out through a slot, c', of the shaft, and a small 75 roller, i, is journaled on the outer end of the stud. This roller i operates between the two cam-rings J and J', by means of which the desired reciprocating movement is given to the pin E. The cam-rings are preferably set 80 in a sleeve, K, the latter being secured to the forward box, F. The pin E, during its engagement with the shuttle, steadies the latter and supports and holds it concentric with the race, and the parts are timed so that this support of 85 the steady-pin comes when it is most needed, when the upward pressure of the shuttle would otherwise be sustained by the points b and b', which would result in these points being soon worn so as to interfere with the perfect working 90 of the shuttle. During the time that the thread is passing across the center of the shuttle the pin E and arm E' are drawn back, the former into the bore of the shaft C and the latter into a recess of the head C', so that they 95 are out of the way of the passing thread. As the forwardly-projecting end of the arm E' enters the recess a³ of the shuttle, by reason of the beveled or inclined part e', the shuttle is advanced a trifle to separate the heel of the 100

shuttle from the driver to allow the thread-loop to pass unobstructed between these parts. What I claim is—

In a sewing-machine, the combination, with

5 a driving-shaft having a reciprocating steady-pin located therein and a revolving shuttle having a recess therein, of an arm attached to the steady-pin, the end of the arm being adapted to enter the recess of the shuttle, said arm

10 having a beveled or inclined surface adapted

to advance the shuttle by engaging the latter, substantially as set forth.

In testimony whereof I sign this specification, in the presence of two witnesses, this 15th day of March, 1887.

D'ARCY PORTER.
